UNITED STATES PATENT OFFICE.

HUGH McCABE, OF LAWRENCE, MASSACHUSETTS.

FLANGING MACHINE.

Application filed June 6, 1924. Serial No. 718,356.

The present invention relates to flanging machines and more particularly to flanging machines of the type described in the McCabe Patent No. 1,408,106, granted February 28, 1922, in which is provided an automatic straining device for imparting a transverse bend to the work to counteract the tendency of the work to buckle during the flanging operation.

10 The object of the present invention is to re-organize and improve the construction of the straining device with the view of obtaining more efficient and economical operation, and with this end in view the present invention consists of the flanging machine hereinafter described and particularly defined in the claims.

In the accompanying drawings, Fig. 1 is a side elevation of the preferred form of flanging machine; Fig. 2 is a front elevation of the clamp members and straining devices; Fig. 3 is a sectional elevation of one of the straining devices, and Fig. 4 is a section on line 4—4 of Fig. 3; Fig. 5 is a sectional elevation of the valve for controlling the admission of air to the straining devices; Fig. 6 is a section on line 6—6 of Fig. 5; Fig. 7 is a section of the upper part of the valve on line 7—7 of Fig. 5; Fig. 8 is a section of the bottom portion of the valve on line 8—8 of Fig. 6; and Figs. 9 and 10 are views similar to Figs. 7 and 8 with the valve in a different position.

The illustrated embodiment of the invention comprises a flanging machine having a bottom clamp member 6, top clamp member 8, a bender 10 and a bender actuating segmental gear 12, all of which are of the form illustrated in the patent above referred to.

40 The gear 12 is operated by a rack (not shown) which is reciprocated by a compressed air cylinder 19 which receives its air supply through a pipe 20. The bottom clamp member 6 is provided with a wedge 22 which is operated to clamp and unclamp the work through the linkages 24 by means of a cylinder 26 which receives its compressed air supply through a connection 28 into the pipe 20. The plate to be flanged is clamped between the clamp members 6 and 8 and the bender 10 is actuated to bend successive increments of the work through a predetermined angle, the work being moved after each bending operation by loosening the bottom clamp member as above described. The relation of the operating

rack to the gear 12 is then changed to bend the flange in successive increments through additional angles, the movements of the rack being controlled by a mechanism 30, which is described in the McCabe Patent 1,460,167, granted June 26, 1923.

The top clamp member 8 has a flat work engaging surface opposite the bottom clamp member and is extended laterally to provide brackets 32 in which the straining devices 34 are received. Each straining device as shown in Fig. 3 comprises a pneumatic straining cylinder having a cylinder head 36 and a base 38 to which the head is secured in the usual manner. The base 38 is provided with a depending sleeve 40 received within an adjusting sleeve 42 which in turn is threaded into the bracket 32. The adjusting sleeve 42 has a right hand thread on its outer surface and a left hand thread on its inner surface so that upon rotation of the sleeve the straining device may be vertically adjusted without turning it on its axis. The adjusting sleeve has a flange 44 provided with spanner receiving openings to permit such adjustment. A plunger 46 is fitted to reciprocate within the sleeve 40 and is connected at its lower end with a swivel bearing plate 47 which bears upon and serves to strain the work (as shown in Fig. 2 and particularly described in the earlier McCabe patent above mentioned). A piston 48 is secured at the upper end of the plunger between a shoulder 50 of the plunger and a nut 52 threaded thereon. The piston is normally urged upward by means of coil springs 54 received in suitable holes formed in the base portion 38 of the cylinder and bearing against the under side of the piston. The plunger 46 is necked down at 56 to form a shoulder which is adapted to be engaged by two locking bolts 58 received in horizontal openings in the base portion 38. The locking bolts are provided with notched ends 60 to afford engagement between the bolts and the plunger, and each bolt is urged away from the plunger by a compression spring 62 which takes against a head 64, of the bolt. Each bolt head is slabbed off, as indicated at 66, to provide a flat upper surface which takes against the under side of the base 38 to prevent turning of the bolts in their openings, thus insuring proper engagement of the notched portions with the shoulder on the plunger. Secured to the bottom of the base are two pneumatic lock-

ing bolt actuating cylinders 70 within which reciprocate pistons 72 bearing against the heads of the locking bolts and adapted to force the latter toward the plunger against the compression of the springs 62 when the cylinders 70 are supplied with compressed air.

The connections for leading air to the cylinders are described as follows: On top 10 of each straining device there is provided an air chest 80 having a port 82 leading into the cylinder 36, and an air chamber 84 connected with the bolt actuating cylinders 70 by tubes 86 and 88, which pass through 15 suitable openings in an annular protecting flange 89 formed on the cylinder head 36. The ports 82 and the chambers 84 of both straining devices are connected together by 20 pipes 85 and 87 respectively. Air is supplied to these pipes from the air connection 28 through a manually operated valve 90 and pressure hose pipes 92 and 94, the former pipe leading to the pipe 85 for the straining cylinders and the latter to the 25 pipe 87 for the bolt actuating cylinders. The valve 90 as illustrated in Figs. 5 to 10 comprises a rotatable valve member 91 having a wrench receiving head 93, and a valve casing 96 provided with an air inlet 98, an 30 outlet 100 connected to the hose 92, an outlet 102 connected with the hose 94, and a relief port 104 opening to the atmosphere. In the position illustrated in Figs. 7 and 8, the air supply is disconnected both from the 35 straining cylinders and the locking bolt operating cylinders, the former having exhausted through the opening 106 in the valve member and the exhaust 104. On turning the handle in a counter-clockwise direction 40 through an angle of 45°, the openings 108, 110 are caused to register with the inlet 98 and the outlet 100 respectively, thus operating the straining plungers; and upon turning the handle through an additional 45° 45 the valve assumes the position shown in Figs. 9 and 10, air being admitted to the straining cylinders through the openings 112, 114 and to the locking bolt operating cylinders through the opening 116 in the bottom portion 50 of the valve. The straining plungers are thus locked in their depressed position to strain the work, the locking bolts being urged under the air pressure to hold the plungers and the swivel bearing plates 47 55 down on the work. After the completion of a bending step, the handle is turned in a clockwise direction through an angle to 45° to relieve the pressure on the bolt actuating cylinders through the relief port 118 which 60 registers with the outlet 102 and opens into the atmosphere through the bottom of the valve, and the pressure on the straining cylinders is thereafter relieved by turning the handle to its Fig. 8 position.

65 In operation the work is clamped by the

clamp members 6 and 8, the straining device having been previously adjusted to give a predetermined strain to the work. The valve 90 is then operated as above described to force down the straining plungers and 70 lock them in position. A portion of the flange is then bent by the bender 10 and the bender is thereafter rotated to its initial position, whereupon the valve 90 is operated to release the straining devices and allow the 75 plungers to rise under the action of the springs 54. The bottom clamp member is then loosened by withdrawing the wedge 22 and the plate is moved to present a new increment to be flanged in the same manner, 80 and so on until a flange is completely formed around the work. As is customary in machines of this type, it is desirable to form the flange in a succession of bending operations; for example, in forming 90° flanges 85 on a circular plate, the whole plate is first formed with a flange approximating 30°, then a second flanging operation is performed to bring the flange down to approximately 60°, and finally the flange is turned 90° down in a third step to 90°. For flanging the successive increments in any flanging operation the adjustment of the straining devices will be kept constant with the assurance that the straining will proceed to the same amount for each increment, but it will be required to vary the amount of straining for the different flanging operations, an adjustment which is conveniently performed between the successive flanging 100 operations by means of the adjusting sleeve 42.

In the foregoing description of the mode of operation of the machine, the work is clamped between the clamp members 6 and 8, and after that the straining device is operated to strain the metal preparatory to bending. If desired the straining device may be operated first, and the clamping of the metal thereafter, the operation of clamping the metal serving to complete its straining preparatory to the flanging operation. This latter mode of operation wherein the straining device is operated first and the clamping afterward is to be preferred in case heavy metal is being flanged, because the clamping wedge is powerful, due to the leverage and toggle of the connections.

Similarly the clamp may be released before the straining device is released. In the case of heavy metal, this is to be preferred because it relieves the bolts 58 of the pressure against them before they are withdrawn.

If desired, both the clamping and the straining devices may be operated at the same time, both in applying and releasing the pressure.

Under some conditions only the lower clamp need be released by withdrawal of the 130

wedge from thereunder; under other conditions only the straining device need be released between successive bending operations.

In some respects the present invention is 5 an improvement on the flanging machine illustrated in the McCabe Patent No. 1,498,974, dated June 24, 1924, which shows straining devices provided with a manually operated lock. According to the present invention the 10 straining control valve may be remote from the straining devices and is conveniently placed near the valves which control the clamping members and the bender segment so that all of the valves may be operated by 15 the workman from one position.

Having thus described the invention, what is claimed is:—

1. A flanging machine having, in combination, means for holding the work, means 20 for flanging the work, a straining device for the work comprising a pneumatic piston adapted to be moved by pneumatic pressure in a direction to strain the work, springs for moving it in the opposite direction, locking 25 means for locking the straining device in work straining position, and springs for withdrawing the locking means from engagement with the straining device.

2. A flanging machine having, in combination, top and bottom clamp members, means 30 for flanging the work, a straining device

carried by one of the clamp members, pneumatic means for operating the straining device, locking means for the straining device, pneumatic means for operating the locking 35 means, and a valve for controlling both the straining device and the locking means.

3. A flanging machine having, in combination, means for flanging the work, a straining device comprising a power cylinder and 40 a piston therein, a plunger and a work engaging member connected with the piston, a locking bolt, a locking bolt actuating cylinder, means for supplying air to the power cylinder and to the locking bolt actuating 45 cylinder, and a valve for controlling the air supply for both cylinders.

4. A flanging machine having, in combination, means for flanging the work, a straining device comprising a straining cylinder, 50 a piston in the cylinder, a plunger connected with the piston, locking bolts for the plunger, locking bolt operating cylinders, an air chest on the straining cylinder having a port communicating with the straining 55 cylinder, and air chamber on the straining cylinder, connections between the air chamber and the locking bolt operating cylinders, and air connections to the air chest port for operating the straining piston and to the air 60 chamber for operating the locking bolts.

HUGH McCABE.
